UNITED STATES PATENT OFFICE.

CEPHAS GILBERT, OF JASPER, FLORIDA.

INTEREST-CALCULATING SYSTEM.

1,208,538.

Specification of Letters Patent. Patented Dec. 12, 1916.

Application filed April 29, 1916. Serial No. 94,470.

To all whom it may concern:

Be it known that I, CEPHAS GILBERT, a citizen of the United States, residing at Jasper, in the county of Hamilton and State 5 of Florida, have invented certain new and useful Improvements in Interest-Calculating Systems, of which the following is a specification.

This invention relates to interest calculating systems and has for its principal object to provide an interest calculating system on cards arranged in convenient filing cabinet.

Another object is to provide a device of 15 this character so constructed that the cards can not be misplaced.

A further object is to provide a device so constructed that the cards may be separated from the remainder of the group without being misplaced.

Other objects such as simplicity, durability, cheapness in manufacture, and the general improvement of the art will be more fully described in the following specification and illustrated in the accompanying drawing in which:

Figure 1 is a perspective view of my device assembled, Fig. 2 is a sectional view of the cabinet showing the cards in position, 30 Fig. 3 is a plan view of one of the cards, and Fig. 4 is a sectional view on the line 4-4 of Fig. 3.

Referring more particularly to the drawings the cabinet comprises a side portion 1, 35 ends 2 and a bottom 3; the bottom 3 having a bearing groove 4 formed adjacent its one edge.

A plurality of cards 5 are mounted in the cabinet. Each of the cards 5 comprises a 40 body portion 6, an index tab 7 and a bearing portion 8. The index tab 7 comprises a projection 9 having an index portion 10 secured thereto by an eyelet 11. The bearing portion 8 comprises a rounded projection 45 having an aperture 12 therein, the aper-

ture 12 having a metal binding 13. The cards 5 are pivotally mounted in the cabinet by a rod 14 which runs through the ends 2 and within the bearing groove 4. The body portions 6 of the cards 5 have interest tables 50 thereon.

The operation of the device is as follows: It being assumed that the cards are all assembled as shown in Fig. 1 and it being desired to compute the interest on a certain 55 amount the correct card is selected by its index tab 7 and it is pulled to the right, this will cause it to revolve on the pivot rod 14 and it will be separated from the other cards and will rest on the tab 7 which 60 serves as a leg or support. When the information desired is obtained it is only necessary to push the card to the left and it will fall into its correct place.

It will of course be understood that I do 65 not wish to limit my invention to an interest calculating system for it will readily be seen that the cabinet and cards I have shown may be used for many other filing systems.

Having thus described my invention what I claim is:

1. In combination with a cabinet having an open top and side and a bearing groove formed in its bottom adjacent said open side, 75 a plurality of cards pivotally mounted therein, said cards comprising a body portion, an index tab, and a bearing projection thereon and having an aperture therein, said aperture having a metal binding.

2. A card for filing cabinets comprising a body portion, an index tab projecting from the side edge of said body portion, and a bearing formed on the corner of said body portion below said tab, said bearing comprising a rounded projection having an aperture therein.

In testimony whereof I hereto affix my signature.

CEPHAS GILBERT.
